F. A. JOSEPH

RUBBER FOOTWEAR ARTICLE

Filed Jan. 25, 1921

UNITED STATES PATENT OFFICE.

FRANK A. JOSEPH, OF NEW HAVEN, CONNECTICUT, ASSIGNOR TO L. CANDEE & COMPANY, A CORPORATION OF CONNECTICUT.

RUBBER FOOTWEAR ARTICLE.

Application filed January 25, 1921. Serial No. 439,745.

This invention relates to a rubber footwear article, more particularly to that type of article known as a foothold, or slip-on.

For light use, particularly by ladies, a type of rubber overshoe has been developed in the trade which is known as foothold or slip-on, and which, instead of entirely covering the shoe, consists merely of a vamp portion and corresponding sole with a rearwardly extending elastic heel strap, the latter at its forward end having a downwardly extending portion adapted to engage the shank of the shoe. The heel strap is necessarily made of a high grade elastic stock in order that it may closely hug the heel portion of a shoe and at the same time withstand the constant stretching to which it is subjected. Both the ordinary type of overshoe and foothold, as previously constructed, have been furnished with an outsole of a relatively inelastic rubber compound and within said outsole is disposed a filler of rag stock or of friction fabric, both of which are also relatively inelastic. Users of overshoes or footholds will usually attempt to use the same pair with shoes varying in shape and width. As a result when an overshoe or foothold having the inelastic sole above described is put on over a shoe which is too wide, the thin upper is considerably stretched and quickly cuts or breaks at the point where it extends over the edge of the shoe sole. In certain types of overshoes such as the rolled edge the outsole is extended at its edge up over the upper, but even in the case of this type of shoe the upwardly extending portion is, of course, made of the same inelastic rubber compound as the outsole, and when stretched by being put over a shoe that is too wide it quickly breaks under the strain.

In footholds as previously constructed the function of the shank portion is to engage the shank of the shoe to prevent the entrance of water or dirt, but the footholds of the prior art are defective at this point in many respects and fail to effectively keep out water. In many of them the shank engaging portion is not extended rearwardly far enough to provide a sufficient bearing surface against the shank of the shoe. In others the inelastic fabric insole or filler sole is extended rearwardly on this shank engaging portion and prevents it from stretching

to closely engage the shank of the shoe. In still others the heel strap is formed with free ends which in manufacture are lapped at this point, thereby thickening the shank engaging portion, reducing its elasticity, and providing an uneven surface for gripping the shoe shank. In still others the outsole, which is formed separate from the shank engaging portion, and of a relatively inelastic rubber compound, as before stated, is lapped over on the shank engaging portion, thereby reducing its elasticity.

An object of my invention is to provide a rubber footwear article capable of fitting shoes of different widths.

Another object is to provide an improved form of foothold.

Still another object is to provide a foothold which will tightly grip the shank of the shoe on which it is worn.

A further object is to reduce the labor, material and number of parts required in making a foothold.

For a complete disclosure of the invention reference is had to the accompanying specification and drawings, in which latter:

Fig. 1 is a side elevation of my improved foothold;

Fig. 2 is a vertical longitudinal section thereof;

Fig. 3 is a transverse section on the line 3—3 of Fig. 2.

Referring to the drawings, the numeral 1 designates the lining of the vamp or upper of a foothold, which lining is formed from any suitable elastic material, preferably stockinet, and superposed on which is the rubber vamp or upper 2. The insole 3 is also formed of an elastic fabric, such as stockinet, instead of the usual woven fabric, and directly secured thereto is a relatively highly elastic outsole 4 of high-grade rubber, said outsole having integral therewith the rear shank engaging portion 5 and the heel strap 6. The outsole 4, shank 5, and strap 6 are died out in a single piece from the sheet stock. The portion 5 is inclined upwardly at a somewhat greater angle than the corresponding shank portion of the shoe for which it is designed. At the sides the shank engaging portion 5 is lapped over the rear edges of the vamp, as shown at 7. The edge of the elastic outsole 4 is extended upwardly on the upper for a considerable dis-

tance as shown at 8. The toe portion of the foothold is reenforced by a gum toe cap 9, and the upper edge of the vamp portion may be ornamented by the binding 10.

5 In use, when the foothold is drawn on the shoe, the longitudinally extended shank engaging portion 5 will grip the shoe shank over a large area, and, due to the elasticity of the stock used, the smooth surface and

10 uniform thickness of the part 5, and its inclination upwardly at a greater angle than that of the shoe shank, it will tightly grip the latter and effectually prevent the entrance of any water or dirt. Should the

15 user wear the foothold on a shoe that is wider than that for which the foothold is intended, the elastic insole 3, outsole 4, and edge extension 8 will stretch to accommodate the increased width, thereby relieving

20 the upper or vamp of the excessive strain and stretching which it formerly had to bear exclusively. In addition the foothold is very easily drawn over the shoe, due to the fact that its sole portion and upturned edges

25 are elastic as well as the upper. Moreover, as the upward edge extension 8 is formed of the same high-grade elastic rubber as the outsole 4, it will readily stretch and bend outwardly without undue strain. Additional advantages are that by making the

30 outsole, upturned edge, shank engaging portion, and heel strap of a single piece of material there is a saving of labor in cutting and assembling the parts, and there is also a

35 saving in the rubber stock formerly required

when overlapping the outsole on the shank engaging portion.

While a specific embodiment of the invention has been shown and described, it is obvious that numerous changes may be made therein without departing from the spirit of the invention, and certain of its features, such as the elastic sole and upturned edge portion, are applicable to other forms of rubber footwear.

Having thus described my invention, what I claim and desire to protect by Letters Patent is:

1. A foothold comprising an upper, an insole, and a one-piece, homogeneous outsole, shank and strap of the same rubber stock, said shank being relatively extended longitudinally and inclined upwardly from the outsole at an angle greater than the shank of its corresponding shoe.

2. A foothold comprising an elastic vamp having an elastic fabric lining, an elastic fabric insole therefor, and a relatively highly elastic one-piece outsole, shank and strap of high-grade rubber, said outsole being disposed next to the insole and extended upwardly on the vamp at its edge, and said shank being relatively extended longitudinally and inclined upwardly at an angle greater than the shank of its corresponding shoe.

Signed at New Haven, Connecticut, this 17th day of January, 1921.

FRANK A. JOSEPH.
